GOLF TEE

Howard Russell Thompson, Des Moines, Iowa

Application June 23, 1931. Serial No. 546,263

3 Claims. (Cl. 273—33)

The object of my invention is to provide a golf tee of simple, durable and inexpensive construction, and of small size, and being so designed that it may be readily and easily pressed into the ground by the player's hand or foot to position with its upper surface level with or below the ground surface, and having a movable cupped ball supporting member, which may be readily and easily raised by the player to an upright position for supporting a ball and when the ball has been struck with a club or the ball supporting member has been struck, the latter will fold down into the body wholly below the ground surface, to thereby provide a golf tee which cannot be dislodged from its position in the ground by a golf club used in driving the golf ball, even though the club should be swung so low as to touch the ground.

A further object is to provide a device of this kind in which the ball supporting member may be readily and easily grasped by the operator and moved to position for supporting the ball after the body is embedded in the ground; and

Further to provide spring actuated means for normally holding the ball supporting member in position above the ground and above the body; and

Further to provide simple and inexpensive means for adjusting the elevation of the ball supporting member relative to the body.

My invention consists in the construction, arrangement and combination of the various parts of the device, whereby the objects contemplated are attained, as hereinafter more fully set forth, pointed out in my claims, and illustrated in the accompanying drawing, in which:

Figure 1 shows a longitudinal sectional view of my improved golf tee. The dotted lines show the ball support in folded position within the body.

Figure 2 shows a sectional view on the line 2—2 of Figure 1.

Figure 3 shows a top or plan view of same; and Figure 4 shows my improved golf tee embedded

in the earth and supporting a golf ball as in use.

Referring to the accompanying drawing, it will be seen that my improved tee comprises two parts. The body portion is preferably made of sheet metal, and its lower end is sharpened at 10 and formed with an earth penetrating point 11. At one end there is a widened upright member 12, and at the upper end thereof is a finger notch 13. The end of the body opposite from the upright 12 is relatively narrow.

Between the walls of the narrow end of the

body, I have inserted a flat lower end 14 of the ball support, the upper end of which is rounded and formed with a cupped ball support 15.

In the body 14 there is a slot 16 with notches 17 at one side. A pivot pin 18 is extended through the body and through the slot for adjustably pivoting the ball support. A pin 19 is provided for limiting the movement of the ball support in one direction.

Mounted within the wide end of the body is a spring 20 so positioned that when the large end of the ball support is forced down into the body, it will engage the spring and the spring will then move a portion of it upwardly above the body, so it may be easily grasped by an operator.

In practical use the pointed end 11 of the tee is placed on the ground with the ball support folded within the body. Then the operator presses his foot upon the body and embeds it in the ground flush with or below the level of the ground. Then the cup shaped ball support is grasped by the operator either because it is projected up above the body slightly by the spring 20, or if no spring is used, the operator may insert a finger through the finger notch 13. The ball retainer is held in an upright position by the pin 19 and it may be adjusted as to height by simply moving it to position with the pin 18 in any one of the notches 17.

It sometimes happens that when a player strikes at a golf ball the club will hit below the ball and even upon the ground surface. In the event that either of these things happens, with my improved tee the result will be that the ball support will be driven to its folded position within the body, and the body will not be dislodged from the ground.

After use, the operator simply grasps the ball support and uses it as a handle to withdraw the body from the ground.

I claim as my invention:

1. An improved golf tee comprising a body portion sharpened at its lower edge and having side walls slightly spaced apart for easy earth penetration, and having an enlarged cup shaped portion near one end, and a golf ball supporting member having a flat body portion inserted between the said side walls and pivotally supported therein and having an enlarged cup shaped end, said golf ball supporting member being capable of standing in an upright position within said body portion and also capable of being moved to a horizontal position wholly contained within the body portion, and means for adjustably pivotally sup-

porting the golf ball holder in various positions of elevation above the body portion.

2. An improved golf tee comprising a body portion sharpened at its lower edge and having side walls slightly spaced apart for easy earth penetration, and having an enlarged cup shaped portion near one end, and a golf ball supporting member having a flat body portion inserted between the said side walls and pivotally supported therein and having an enlarged cup shaped end, said golf ball supporting member being capable of standing in an upright position within said body portion and also capable of being moved to a horizontal position wholly contained within the body portion, and a spring for normally holding the cup shaped portion of the golf ball holder above the edges of the side walls of the said body portion, for the purposes stated.

3. An improved golf tee comprising a body por-

20

tion formed of two side walls and an end wall, the side walls and the end wall being tapered at their lower ends for easy earth penetration, the said end wall being substantially upright, and the side walls adjacent said end wall being flared outwardly at their upper edges to form a cup shaped recess, and the said side walls at the end opposite from the upright end wall being slightly spaced apart and substantially parallel, and a golf ball supporting member having a flat body portion inserted between the side walls and pivotally supported therein and having an enlarged cup shaped end and so shaped that when in an upright position it will be capable of receiving and supporting a golf ball and when turned to a substantially horizontal position it will enter said cup shaped portion of the body.

HOWARD RUSSELL THOMPSON.
